UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNEES TO VICKERS SONS & MAXIM, LIMITED, OF WESTMINSTER, ENGLAND.

AMMUNITION HOISTING AND LOADING APPARATUS FOR ORDNANCE.

996,222.

Specification of Letters Patent. Patented June 27, 1911.

Application filed November 17, 1908. Serial No. 463,118.

To all whom it may concern:

Be it known that we, ARTHUR TREVOR DAWSON and JAMES HORNE, both subjects of the King of Great Britain, residing, respectively, at 32 Victoria street, Westminster, in the county of London, England, and Naval Construction Works, Barrow-in-Furness, in the county of Lancaster, England, have invented certain new and useful Improvements in Ammunition Hoisting and Loading Apparatus for Ordnance, of which the following is a specification.

This invention relates to ammunition hoisting and loading apparatus for ordnance and is especially adapted for use with turret guns mounted singly or otherwise on board ship or elsewhere.

Heretofore in the usual form of hoisting apparatus, the projectile and powder charges have been brought up from their magazine or storage places, on a hoisting cage whence they have been transferred to a loading cage in the working chamber and by the said loading cage have been elevated to a point behind the breech of the gun ready to be rammed into the said breech. The loading cage has also in some cases been so arranged that when it has been elevated into alignment with the breech of the gun, it will be capable of following the movements of the gun in its changes in elevation, so as to always occupy the correct loading position.

According to our invention we provide a hoisting cage, which, although loaded and raised in the well-known manner, is adapted to be brought to such a position contiguous to the gun as to permit of the ready transfer of the projectile and powder charges to a receiving or loading cage attached to one side of the gun slide or other part of the mounting that moves with the gun. The said receiving cage is so constructed and arranged that after receiving the powder charges and the projectile it can be caused to swing or otherwise assume a position behind the breech of the gun to permit of the ready transfer or loading of the ammunition from the receiving cage into the gun, in whatever position of elevation or depression the latter may assume and whether it is in motion or at rest.

In order that our said invention may be clearly understood and readily carried into effect we will describe the same more fully

with reference to the accompanying drawings, in which:—

Figure 1 is a sectional side elevation. Fig. 2 a sectional plan, and Fig. 3 a sectional rear elevation showing our improvements applied to a two-gun turret. Fig. 4 is a side elevation, and Fig. 5 is a plan showing on a larger scale, the hoisting and receiving cages in the position they occupy when the hoisting cage has been elevated into alignment with the receiving cage. Fig. 6 is an end view of the hoisting cage, and Fig. 7 is an end view of the receiving cage. Figs. 8, 9, 10 and 11 are views similar to Figs. 4, 5, 6 and 7 but showing the means for operating the doors of the hoist and the receiving cage.

In all these figures like letters of reference indicate similar parts.

A is the hoisting cage and B is the receiving cage. The hoisting cage is loaded in the magazines at the lower end of the rotary trunk A' in the usual manner, the projectile and powder charges lying horizontal or thereabout. The said hoisting cage is guided in its movements up and down the rotary trunk by rails A² extending from the magazines to a suitable position at one side of the breech end of the gun. In the example shown the said hoisting cage is raised by a hydraulic press A³ and a hoisting rope A⁴ (Fig. 1) which is carried over suitable guide pulleys or sheaves A⁵ A⁶ A⁷ A⁸ and attached to the hoisting cage. The arrangement of the guide pulleys is adapted to provide for the usual compensating action, so as to maintain the hoisting cage, when it is raised, in its correct relative position to the receiving cage B, whether the gun is in motion (changing its angle of elevation) or at rest. In Fig. 1 the sheave A⁷ is carried by the gun slide C so that when the angle of elevation is changed the length of rope connected with the cage will be correspondingly altered to permit of the cage following the movement of the gun and of the receiving cage. The upper parts of the guide rails A² are curved to form arcs concentric with the gun trunnions, in order that the cage A will remain in the required relative position to the receiving cage. The said receiving cage is in Fig. 1 directly attached to an arm B' connected to the gun mounting and forming a prolongation of the slide frame. This cage will therefore always move in an arc

concentric with the gun trunnions when changes in the angle of elevation of the gun occur and will maintain its alinement with the breech of the gun so as to always pre-
5 serve the proper loading position. The said receiving cage can be either completely carried by the arm B' or can be supported on suitable guide rails B² and held in position by the said arm, the guide rails being curved
10 to form an arc concentric with the gun trunnions and the guide rails A² as shown.

The transference of the ammunition from the hoisting cage H is in the example shown intended to be effected by a rammer D at-
15 tached to the gun slide or mounting so that it changes its position to accord with the changes in position of the gun in varying its angle of elevation, and therefore always lies in line with the ammunition trays of
20 the receiving cage B and the hoisting cage A when the latter is in its raised position. This rammer is preferably actuated hy-
draulically, but it may be adapted to be ac-
tuated by any other appropriate motive
25 power or by hand.

The receiving cage B is so constructed that the ammunition can be moved laterally into a position of alinement with the gun breech for loading into the gun. For this
30 purpose the said receiving cage is in the ex-
ample shown made in two parts, one part B^x being in the form of a frame which is at-
tached to the aforesaid arm B' and guided by suitable rollers on the aforesaid rails B²,
35 and the other part B^x is pivotally connected at b^x to the frame. The said pivotal part, after it has been loaded with the ammu-
nition from the hoisting cage A, can be swung
40 inward into an oblique position behind the breech of the gun with its lower end in aline-
ment with the center of the same as shown by the dotted lines in Fig. 7. The projec-
tile which lies at the bottom of the pivotal
45 part of the receiving cage thus lies in aline-
ment with the bore of the gun and can be
pushed into the breech by a rammer E of
the usual or other appropriate type. After
50 the projectile has been introduced into the
gun the rammer is retracted and the powder
charges are permitted to descend into the
lower end of the pivotal part of the receiv-
ing cage and are in turn introduced into the
55 gun by the rammer, suitable gear or mech-
anism being provided on the said cage for
permitting the powder charges to descend
one at a time into the loading position, such
for example as that set forth in the specifica-
tion of our prior British Patent No. 3498 of
1907. The aforesaid rammer may be carried
60 directly on a bracket or arm forming a rear
extension of the gun slide, in which case it
will always lie in alinement with the bore of
the gun irrespective of the changes in ele-
vation of the gun. Or it may be of the type
65 in which the rammer is movably supported

on a structure or frame E' carried on the gun platform at the rear of the gun as shown in Fig. 1 and having suitable flexible connections such as a chain, wire rope or the like from the gun slide or cradle, so ar-
ranged as to maintain the rammer head in line with the bore of the gun within the load-
ing limits or zone when the gun changes its
angle of elevation.

To operate the pivotal part of the receiv-
ing cage B so as to bring the lower end into
alinement with the breech of the gun, we
have shown a hydraulic ram b, arranged
70 to operate a lever b' connected by means of
a link b² to an arm b³ at the upper end of
the cage, so that when motive fluid is per-
mitted to act on the ram it causes the pivotal
part of the cage to swing inward into the
75 oblique position before stated, with the lower
end in alinement with the gun breech. Other
forms of motive power and devices can how-
ever be used for effecting the swinging move-
ment of the pivotal part of the cage.

Spring controlled or other form of doors
a^x and b^x may be fitted to the adjacent ends
80 of the hoisting cage and the receiving cage
so as to protect the powder charges and these
doors may be arranged to open and close au-
tomatically.

Referring to Figs. 8, 9, 10 and 11 the cage
A is provided with a cam a' which when the
cage reaches its top position actuates a lever
b⁴ pivoted on the cage B. To the said lever
b⁴ is attached a bevel wheel b⁵ which in turn
rotates a bevel pinion b⁶ keyed to the hinge
pin b⁷ of one of the doors b^x of the cage B.
The two doors b^x are connected by means of
levers b⁸ and b⁹ and a connecting rod b¹⁰.
The said doors are closed by means of a
spring b¹¹.

The doors a^x of the cage A are opened by
the outward movement of the rammer D.
The tappet bolt d' is restrained from out-
ward movement by the head of the rammer
D and as the rammer moves the spring d²
110 forces the bolt d' outward against the slid-
ing bar a³ carried by the cage A. The bar
a³ acting through a connecting rod a⁵ and a
lever a⁶ rotates the hinge pin a⁷ of the door
a^x. The two doors a^x are coupled together by
115 levers a⁸ and a⁹ and a connecting rod a¹⁰.
When the bolt d' is withdrawn the doors a^x
are closed by a spring a⁴ acting against a
collar on the bar a³.

What we claim and desire to secure by
Letters Patent of the United States is:—

1. In ammunition hoisting and loading
apparatus for ordnance, the combination of
a hoisting cage for raising the projectile and
powder charges together to a position con-
tiguous to the gun, a receiving or loading
cage connected with the gun mounting so as
125 to move when the angle of elevation of the
gun is changed, means for transferring the
projectile and the powder charges from the
130

hoisting cage to the receiving or loading cage, and means for causing the said receiving or loading cage to assume the loading position behind the gun breech.

- 5 2. In ammunition hoisting and loading apparatus for ordnance, the combination of a hoisting cage for raising the projectile and powder charges together to a position contiguous to the gun, means for causing the 10 said cage, when raised, to follow the movements of the gun in its changes in elevation or depression, a receiving or loading cage connected with the gun mounting so as to move when the angle of elevation of the gun 15 is changed, means for transferring the projectile and the powder charges from the hoisting cage to the receiving or loading cage, and means for causing the said receiving or loading cage to assume the loading 20 position behind the gun breech.

3. In ammunition hoisting and loading apparatus for ordnance, the combination of a hoisting cage for raising the projectile and powder charges together to a position contiguous to the gun, a receiving or loading cage comprising a fixed part connected to the gun mounting and a second part pivotally connected with the said fixed part, means for transferring the projectile and 25 the powder charges from the hoisting cage to the receiving or loading cage, and means for swinging said pivotal part of the cage into the loading position behind the gun breech.

- 35 4. In ammunition hoisting and loading apparatus for ordnance, the combination of a hoisting cage for raising the projectile and powder charges together to a position contiguous to the gun, a receiving or loading 40 cage comprising a fixed part connected to the gun mounting and a second part pivotally connected with the said fixed part, means for transferring the projectile and powder charges together from the said 45 hoisting cage to the pivoted part of the receiving or loading cage and means for swinging said pivotal part of the receiving or loading cage into the loading position behind the gun breech.

- 50 5. In ammunition hoisting and loading apparatus for ordnance, the combination of a hoisting cage for raising the projectile and powder charges together to a position contiguous to the gun, means for causing the

said cage, when raised, to follow the movements of the gun in its changes in elevation or depression, a receiving or loading cage, a slide frame for the gun, an arm forming a prolongation of said slide frame and upon which the receiving or loading cage is 55 mounted, means for transferring the projectile and the powder charges from the hoisting cage to the receiving or loading cage, and means for bringing the said cage into the loading position behind the gun 60 breech.

6. In ammunition hoisting and loading apparatus for ordnance, the combination of a hoisting cage for raising the projectile and powder charges together to a position contiguous to the gun, a hydraulic press and a hoisting rope for raising said cage, a slide frame for the gun, a sheave over which said hoisting rope is passed carried by said slide frame, a receiving or loading cage connected 70 with the slide frame for the gun, means for transferring the projectile and the powder charges from the hoisting cage to the receiving or loading cage, and means for bringing the said cage into the loading position be- 75 hind the gun breech.

7. In ammunition hoisting and loading apparatus for ordnance the combination of a hoisting cage for raising the ammunition to a position contiguous to the gun, means 85 for causing the said cage, when raised to follow the movements of the gun in its changes in elevation or depression, a slide frame for the gun, a receiving or loading cage mounted on said slide frame, a rammer 90 on said frame for transferring the ammunition from the hoisting cage to the loading or receiving cage, means for bringing the said receiving or loading cage to the loading position behind the gun breech, and a ram- 95 mer for transferring the ammunition from the receiving or loading cage to the gun.

In testimony whereof we affix our signatures in presence of two witnesses.
